Attorney.

UNITED STATES PATENT OFFICE.

JOHN F. BLOOM, OF ST. JOSEPH, WISCONSIN.

VALVE.

1,329,881.

Specification of Letters Patent.

Patented Feb. 3, 1920.

Application filed February 12, 1919. Serial No. 276,519.

To all whom it may concern:

Be it known that I, JOHN F. BLOOM, a citizen of the United States, residing at town of St. Joseph, in the county of St. 5 Croix and State of Wisconsin, have invented certain new and useful Improvements in Valves, of which the following is a specification.

This invention relates to oscillating valves 10 operated by hand and adapted to distribute fluid under pressure, such as steam, water or air, from an inlet to an outlet, and from the said outlet to an exhaust; and it consists in the novel construction and combination 15 of the parts hereinafter fully described and claimed.

In the drawings, Figure 1 is a front view of two similar three-way valves constructed according to this invention and combined together so as to operate in conjunction. Fig. 2 is a longitudinal section through the right hand three-way valve shown in Fig. 1, showing the inlet closed and the outlet connected with the exhaust. Figs. 3 and 4 are cross- 25 sections through the right hand three-way valve, taken on the line $x-x$ in Figs. 1 and 2. Fig. 3 shows the inlet connected with the outlet, and Fig. 4 shows the outlet connected with the exhaust. Fig. 5 is a cross-section 30 similar to Fig. 3, but is taken through the left hand three-way valve on the line $y-y$ in Fig. 1, and shows the outlet connected with the exhaust, which is the setting which corresponds with that of the right hand 35 valve as shown in Fig. 3. Fig. 6 is a cross-section, taken on the line $z-z$ in Fig. 1, and shows the valve operating mechanism.

This valve may be used to distribute pressure fluid to a press of any approved 40 construction, or it may be used in connection with a system of fire-extinguishing apparatus, and also for many other purposes. When used in conjunction, as shown in Fig. 1, the two similar three-way valves are arranged 45 right and left. As both of these valves are alike the following description will be confined to one of them.

The body portion of the valve is formed 50 of two separate casings 2 and 3, which are secured upon a base 4 common to both of them, or which are otherwise held relatively stationary. These two casings have a tubu-

lar sleeve 5 secured inside them and extending between them. A valve 6 is arranged to oscillate inside the sleeve, and is tapered 55 slightly, and is fitted by grinding it, so that there may be no leak between it and the sleeve. The valve 6 is hollow, and is provided with two chambers 7 and 8, arranged 60 end to end and separated by a partition 9. 60

The valve is operated or oscillated by means of a stud or shaft 10 which is secured to its smaller end. A handle 12 may be secured directly to this stud, but it is preferably pivoted in a bracket 14 secured to the 65 base 4. This handle is provided with a toothed segment 15 which gears into a toothed pinion 16 secured on the stud or shaft 10. The stud 10 is preferably square, and in the valve shown in Fig. 1 the pinion 70 16 engages with the operating studs of both the three-way valves.

The smaller end portion of the valve and the adjacent end of the sleeve are kept tight by means of a gland 17, which is secured to 75 the casing 2, and a suitable cup-packing 18.

The adjacent ends of the two casings 2 and 3 are kept tight with the sleeve by means of two similar glands 19 and packings 20. The other end portion of the sleeve has 80 a circumferential rib 21 formed on it, and this rib engages with an internal rib 22 formed on the casing 3. This end portion of the sleeve has a cylindrical chamber 24 formed in it, and 25 is a cover which is se- 85 cured to the casing 3 by bolts 26.

This cover has a tubular extension 27 which fits inside the chamber 24 and forms an annular passage 28 around the end portion of the sleeve. Packing material 29 is 90 arranged between the end of the extension 27 and the two ribs 21 and 22; and packing material 30 is also arranged between the cover 25 and the end of the casing 3.

A pointed adjusting screw 31 engages 95 with the cover 25 and bears against the end of the valve 6 at its axis, and operates to adjust the contact between the valve and the sleeve. The sleeve 5 is not fitted tightly in the two casings, but is kept tight in them 100 by packing material as hereinbefore described. This construction permits the valve and its sleeve to be taken out and replaced as often as the wear between them

makes it desirable, and as this valve is used for distributing fluid under high pressure it is essential that the valve and its sleeve should be kept in very good working condition.

The inlet 32 of the casing 2 communicates with a suitable inlet pipe 33 secured to the casing 2 by any approved means. The casing 2 has an annular passage 34 which communicates constantly with the inlet 32 and also with two inlet ports 35 formed in the sleeve 5, and arranged at opposite sides of it to balance the pressure. The chamber 7 of the valve is provided with two inlet ports 36 for communicating with the ports 35.

The other casing 3 has a relatively long annular passage 36 formed in it and arranged around the sleeve 5. This passage 36 communicates constantly with two similar outlet ports 37 formed in the sleeve and arranged at opposite sides of it, and also with an outlet port 38 formed in the casing. The outlet port 38 of the casing is connected with any suitable outlet pipe 39 secured to the casing. The chamber 7 of the valve is provided with two outlet ports 40 for communicating with the outlet ports 37 in the sleeve.

The chamber 8 of the valve is provided with a pair of ports 42 arranged at opposite sides of it, and adapted to communicate with a pair of ports 43 formed in the sleeve which communicate constantly with the annular passage 36 in the casing 3. These ports 43 are shown in dotted lines in Fig. 2, and they are preferably much wider than the ports 42 in the valve so that two similar valves can be arranged right and left as shown in Fig. 1, without any change or alteration to their ports.

The chamber 8 of the valve is also provided with a pair of exhaust ports 45 arranged at opposite sides of it and adapted to communicate with a pair of wide ports 46 formed in the sleeve, and which are made wide for the same reason as the ports 43. The ports 46 communicate constantly with the annular passage 28 of the tubular extension 27 of the cover 25 hereinbefore described. This tubular extension 27 has an exhaust port 47 which connects the annular passage 28 with an exhaust port 48 in the casing 3, and this exhaust port 48 communicates with any suitable exhaust pipe 49 secured to the said casing.

When the valve is moved to the position shown in Fig. 3, the pressure fluid passes from the inlet pipe 33 to the outlet pipe 39; and when the valve is moved to the position shown in Figs. 2 and 4, the pressure fluid passes from the outlet pipe 39 to the exhaust pipe 49.

The left hand three-way valve shown in Fig. 1 is set in a position relative to the

right hand valve, so that the left hand valve 65 is exhausting the fluid from its outlet pipe when the right hand valve is admitting pressure fluid to its own outlet pipe. These combined valves have their inlet pipes formed as a forked pipe having a single inlet branch 50.

What I claim is:

1. A three-way valve, comprising two separate casings, a single sleeve removably secured in the said casings, a valve mounted to oscillate in the said sleeve, and packing devices between the two casings and the said sleeve and between the valve and the sleeve, the said casings, sleeve and valve being provided with suitable ports and passages for the distribution of pressure fluid.

2. A three-way valve, comprising two separate casings, a single sleeve removably secured in the said casings, a tapering valve mounted to oscillate in the said sleeve, means for pressing the said valve endwise into working engagement with the said sleeve, and packing devices between the two casings and the said sleeve and between the valve and the sleeve, the said casings, sleeve and valve being provided with suitable ports and passages for the distribution of pressure fluid.

3. A three-way valve, comprising two separate casings, a single sleeve removably secured in the said casings, a valve mounted to oscillate in the said sleeve, a gland secured to one casing and operating to prevent leak between the sleeve and one end portion of the valve and between the sleeve and the said casing, packing devices between the adjacent end portions of the two casings and the middle part of the sleeve, and packing devices between the sleeve, valve and the other casing at the other end portion of the valve from the said gland, the said casings, sleeve and valve being provided with suitable ports and passages for the distribution of pressure fluid.

4. A three-way valve, comprising two separate casings, a single sleeve removably secured in the said casings, a valve mounted to oscillate in the said sleeve, packing devices between the casings and the sleeve and between the sleeve and one end portion of the valve, circumferential ribs on the said sleeve and on one casing which bear against each other, and a cover secured to the said casing over the other end portion of the valve and provided with a tubular extension which projects within the said casing and forms a joint over the said ribs, the said casings, sleeve, tubular extension and valve being provided with suitable ports and passages for the distribution of pressure fluid.

5. A three-way valve, comprising two separate casings, a single sleeve removably secured in the said casings, a hollow valve

mounted to oscillate in the said sleeve and provided with a partition dividing it into two chambers arranged end to end, and packing devices between the two casings and the said sleeve and between the valve and the sleeve, the said casings, sleeve and valve being provided with suitable ports and

passages for distributing pressure fluid through them and the said chambers of the valve.

10

In testimony whereof I have affixed my signature.

JOHN F. BLOOM.
